FUEL INJECTOR PUMP

John W. Berhman, Lincoln Park, and Raymond L. Robiolo, Paterson, N. J., assignors, by direct and mesne assignments, of forty percent to Federal Industrial Corporation, Paterson, N. J., a corporation of New Jersey, and sixty percent to Charles W. Brooks, Montclair, N. J.

Application October 31, 1935, Serial No. 47,534

7 Claims. (Cl. 103—145)

Our invention relates to improvements in pumps.

One of the objects of our invention is to provide an improved construction for a pump of the type more particularly adapted for fuel injection in Diesel engines, and which has advantages over the various constructions proposed heretofore in the way of efficiency and reliability of operation at relatively high speeds of operation and conditions of relatively high output pressures.

Another object of our invention resides in the provision of an improved construction for a pump of the character referred to which is relatively simple as compared with the various constructions proposed heretofore.

Other objects and advantages will hereinafter appear.

For the purpose of illustrating our invention, an embodiment thereof is shown in the drawings, in which

Figure 1 is a longitudinal sectional view of a pump constructed and operating in accordance with our invention;

Figs. 2 and 3 are sectional views taken on the lines 2—2 and 3—3, respectively, in Fig. 1;

Fig. 4 is a sectional view similar to Fig. 2, showing a modification;

Fig. 5 is a plan view of Fig. 1, part of the pump casing being broken away to show the interior;

Fig. 6 is an elevational view looking toward the left in Fig. 5;

Figs. 7 and 9 are sectional views similar to Fig. 2, showing modifications;

Fig. 8 is a view partly in section, the section being taken on the line 8—8 in Fig. 7;

Fig. 10 is a perspective view of the assembly of the pumping parts in Fig. 1;

Figs. 11 and 12 are detail perspective views of two of the parts in the assembly shown in Fig. 10;

Fig. 13 is a simplified, fragmentary view, showing a modification; and

Fig. 14 is a fragmentary view taken from Fig. 9, showing a modification.

With reference to Fig. 1, our improved pump comprises a casing 10 provided with an annular pump or pressure chamber 12 concentric about its longitudinal axis. The pumping action is effected by complementary pumping parts 14 and 16, each being in the form of a segment of a ring concentric about the longitudinal axis of the pump casing, as more clearly shown in Fig. 2. The part 16 has a sliding fit in the pump chamber for rocking movement about the longitudinal

axis of the pump casing relatively with respect to the part 14 which is fixed against movement in the casing.

The pumping part or member 16 is integral with a hollow head 20 on the end of a driving shaft 22 which extends outwardly and beyond the pump casing through a cover plate 24 and a nut 26 screwed thereon to hold packing 28 in place about the shaft.

For the purpose of imparting rocking movement to the shaft 22 and the pumping part 16, a rotating cam 30 is caused to engage a roller 32 on the end of an arm 34 fixed on the shaft. The cam 30 causes rocking movement of the pumping part 16 in a clockwise direction, as viewed in Fig. 2, from the position shown through an angle slightly less than the angle α , so that the face 36 of the part 16 is then close to but does not engage the adjacent face 38 of the part 14. During this stroke of the part 16, oil or other liquid previously admitted into the pump chamber between the adjacent faces 36 and 38 is forced therefrom and expelled from the pump casing by the way of an outlet passage 40 and a check valve 42 of conventional design. As the high part of the cam 30 leaves the roller 32 at the end of the pumping stroke, the shaft 22 is allowed to rotate back under the action of a coil spring 44 having one end fixed to the packing nut 26 and its other end engaged with the arm 34. The cam surface is such that the part 16 is allowed to rotate back until it engages lightly with the abutment 14, or such that at the end of the return stroke the part 16 falls slightly short of the part 14. As shown in Fig. 6, the arrangement is such that the direction of force on the nut 26, due to the tension in the spring 44, is the same as the direction of rotation of the nut to tighten it with respect to the cover plate 24.

A compression spring 45 may be used in lieu of the coil spring 44, as shown in Fig. 13.

The cover plate 24 is secured to the pump casing by screws 46 which may be locked against loosening by a wire 48 extended and tightened about the screw heads as shown in Figs. 5 and 6.

For the purpose of controlling the volume of oil or liquid expelled through the valve 42 for each stroke of the pumping part 16, a valve element 50 is provided, this being disposed within the pumping parts or members 14 and 16 and having a sliding fit with respect thereto. The element 50 is rotated about the longitudinal axis of the pump casing by a control shaft 52 with which it is integral and which extends outwardly beyond the casing through a packing nut 54 screwed on 55

the outer end of a nipple 56 having a press fit in the pump casing and with which the part or abutment 14 is integral. Leakage between the shaft 52 and nipple 56 is prevented by packing 58 held in place by the nut 54. The control shaft 52 is rotated by an arm 60 fixed to the outer end thereof.

The oil or liquid to be pumped is admitted into the pump chamber by way of an inlet connection 10 62, an annular groove 64 in the pump casing, a passage 66 and a communicating annular groove 68 in the nipple 56, and passages 70 and 72 in the control shaft 52. The valve element 50 is drilled to provide passages 74 through which the oil or liquid passes from the passage 72 into the pumping chamber 12, or in the opposite direction from the pump chamber back into the passage 72.

The control or apportionment of the volume 20 of oil pumped through the check valve 42 for each stroke of the rocking part 16 is obtained by rotation of the control shaft 52 to position the 25 passages 74 with respect to the face 36 when the pumping part 16 is in the position shown in Fig. 2 and about to begin the pumping stroke. With the parts in their respective positions, the 30 control element 50 being in the "full-throttle" position, as shown in Fig. 2, the passages 74 are closed shortly after the pumping part 16 starts the pumping stroke, so that practically all of the 35 oil between the adjacent faces 36 and 38 will be pumped out through the valve 42. However, if the control element 50 is rotated in a clockwise direction to place the passage 74 in any desired 40 intermediate position, the oil, during the corresponding initial part of the operating stroke will be pumped back through the passages 74 into the intake passage and until the part 16 reaches the position where it closes the passages 74, after 45 which the oil remaining between the adjacent faces 36 and 38 will be forced out through the valve 42.

From the foregoing it will be seen that the apportionment of the oil or liquid pumped during 45 each pumping stroke of the part 16 is possible by simply adjusting the control shaft 52 to the desired position, and that this can be done during normal operation of the pump and conveniently from a remote point through a suitable mechanical connection with the arm 60, as will be well 50 understood.

The pressure of the liquid in the inlet passage of the pump is relatively low and only such as to insure that, for the particular rate of operation required, the rate of flow of the oil or liquid 55 through the passages 74 into the pump chamber 12 is adequate to fill this chamber during the period in the operating cycle that the passages 74 are uncovered by the pumping part 16. A packing ring 76 and a nut 78 are applied to the outer end of the nipple 56 to provide a seal at this point and to hold the part or abutment 14 in a fixed position with respect to the pump casing. If desired, a pin 80 may be used 60 to further insure against rotation of the nipple 56 and the abutment 14 with respect to the pump casing.

When a group of pumps are used, the individual pumps operating respectively to serve the cylinders of a multi-cylinder Diesel engine, for example, it is proposed to connect them in series in the supply line. For this purpose, the pump is provided with a connection 82 which communicates with the annular passage 64 in the pump casing. A pipe 83 then leads from the connection 75

82 of any particular pump to the connection 62 of the pump next in the series. It will be understood that the pressure in the common supply line is then maintained sufficiently high to insure the supply of oil or liquid to all of the pumps at a rate sufficient for the particular rate of operation.

If the liquid being pumped is not a sufficient lubricant itself, it is proposed to provide the pump casing with a lubricating passage 84, as shown in Fig. 4, which will always be in communication with a passage 86 in the pumping part 16. Oil is then supplied by way of a connection 88 to lubricate the adjacent surfaces of the pump casing and the part 16, and the adjacent surfaces of the part 16 and the control element 50.

At the higher rates of operation, it might be required that the rate of flow between the passage 72 and the pump chamber 12 be substantially greater than is possible in the construction shown in Figs. 1 to 6. In such cases, it is proposed to modify the construction as shown in Figs. 7 and 8 by providing the control element 50 with a radial passage 90 and the pumping part 16 with a passage 74a which is always in communication 25 with the pump casing 12 by way of an annular groove 92 cut in the outer face of the part 16. The arrangement is such that the passage 74a is opened and closed by the control element 50 at the same time that the passages 74 are opened 30 and closed by the pumping part 16. It will be seen that this construction is the equivalent of making the passages 74 larger or greater in number, which change might not be possible or practical. The construction and manner of operation 35 in Figs. 7 and 8 are otherwise the same as that in Figs. 1 to 6.

In the modification shown in Fig. 9, the oil or liquid is supplied by way of an inlet connection 94 to a point 96 which is in front of the face 36a 40 of the pumping part 16a when the latter is in the position shown, and about to begin the pumping stroke. The control element 50a, corresponding to the control element 50 in Figs. 1 to 6, is provided with the passages 98 and 100 and the annular groove 102 in its outer face, disposed and communicating as shown.

With the parts in their respective positions as shown in Fig. 9, the passage 98 will be uncovered as soon as the part 16a starts its stroke in a clockwise direction, whereupon the oil, instead of being pumped out through the valve 42 escapes by way of the passages 102, 100, 98 and a communicating annular passage 104 in the pump casing, 50 back into the supply line.

It will be seen that upon clockwise rotation of the control element 50a to place the passage 98 in a different position, it will be closed by the part 16a during the first part of the pumping stroke, at which time the only outlet for the oil 60 will be through the valve 42. When the passage 98 is uncovered by the part 16a during the remaining part of the pumping stroke, the oil instead of being forced out through the valve 42 will be pumped back into the feed line through 65 the passages 102, 100, 98, and 104.

It will be noted that in the embodiment of our invention shown in Fig. 9, any pumping of oil through the valve 42 takes place during the first part of the operating stroke, after which the control passages are opened to cause the oil to be pumped back into the supply line. On the other hand, in the embodiments of our invention shown in Figs. 1 to 8, the relief passages are opened during the first part of the pumping stroke, after 70 75

which these passages are closed and the oil then forced out at the high pressure through the outlet valve 42. During the return or back stroke of the pumping part 16a in Fig. 9, sufficient back pressure might develop on the output side to cause the oil to be pumped through the passages 98 and 100 and thence through the outlet valve 32, rather than out in the opposite direction through passage 104 into the intake line 94. To prevent this, it is proposed to place a suitable check valve 106 in the passage 100 as shown in Fig. 14. As shown, this valve closes with the pressure on the intake side so that oil can only flow through the passages 98 and 100 toward the pumping chamber 15 and the outlet valve 42.

From the foregoing it will be seen that we have provided an improved construction for pumps which operates efficiently at relatively high pressures and relatively high speeds of operation, and 20 which is rugged and simple in construction.

While we have described the various embodiments of our invention more in connection with use as fuel injector pumps for Diesel oil engines, it will be understood that our invention has a 25 much broader aspect in the sense that a construction embodying our invention can be used in other environments, such as for the pumping or circulating of oil in hydraulic brake or shock-absorber systems for automobiles.

It will be understood that various changes and 30 modifications other than those described can be made without departing from the spirit of our invention or the scope of the claims.

We claim as our invention:

1. In a pump of the character described, a casing 35 provided with an annular pump chamber concentric about its axis, complementary pumping parts disposed in said chamber and each being in the form of a segment of a ring concentric about said axis, one of said parts having a sliding fit in said chamber for rocking movement about said axis relatively with respect to the other part, said pump being provided with an inlet passage 40 for the admission of liquid into said chamber between adjacent ends of said parts, said pump being provided with an outlet passage for the expulsion of the liquid from between said ends, means for controlling the volume of liquid expelled through said outlet passage for each stroke 45 of said rocking part, and means for imparting rocking movement to said one of said parts.

2. In a pump of the character described, a casing 50 provided with an annular pump chamber concentric about its axis, complementary pumping parts disposed in said chamber and each being in the form of a segment of a ring concentric about said axis, one of said parts having a sliding fit in said chamber for rocking movement about said axis relatively with respect to the other part, said 55 pump being provided with an inlet passage for the admission of liquid into said chamber between adjacent ends of said parts, said pump being provided with an outlet passage for the expulsion of the liquid from between said ends, spring 60 means for imparting movement to said rocking part in one direction, and means for imparting movement to said rocking part in the opposite direction against the action of said spring means.

3. In a pump of the character described, a casing 65 provided with an annular pump chamber concentric about its axis and with a member disposed and fixed in said chamber, a pumping member disposed in said chamber and being in the form of a segment of a ring concentric about said axis and having a sliding fit in said chamber

for rocking movement about said axis, said pump being provided with an inlet passage for the admission of liquid into said chamber between adjacent faces of said members, said pump being provided with an outlet passage for the expulsion 5 of the liquid from between said faces, means for controlling the volume of liquid expelled through said outlet passage for each stroke of said pumping member and being in the form of a valve part 10 having a sliding fit with respect to said members and being rotatable about said axis, means for rotating said control member, and means for imparting rocking movement to said pumping member.

4. In a pump of the character described, a casing 15 provided with a member disposed and fixed therein, a pumping member disposed in said casing and having a sliding fit therein for rocking movement about the axis of said casing, said pumping member being provided with a part 20 complementary to said fixed member and in the form of a segment of a ring, said pump being provided with an inlet passage for the admission of liquid into said casing between adjacent faces of said fixed member and said part, said pump 25 being provided with an outlet passage for the expulsion of the liquid from between said faces, means for controlling the volume of liquid expelled through said outlet passage for each stroke 30 of said pumping member and being in the form of a valve element disposed in said pumping member and rotatable with respect thereto about said axis, means for rotating said element, and means for imparting rocking movement to said pumping member.

5. In a pump of the character described, a casing, complementary pumping parts disposed within said casing and being in the form of segments 35 of a ring concentric about the same axis, one of said segments having a sliding fit in said casing for rocking movement with respect to the other part, said pump being provided with an inlet passage for the admission of a liquid into said casing between said segments, said pump being provided 40 with an outlet passage for the expulsion of the liquid from between said segments, means for controlling the volume of liquid expelled through said outlet passage for each stroke of the rocking segment and being in the form of a valve element disposed within said segments and rotatable 45 about said axis, a drive shaft extending outwardly from said rocking segment and beyond said casing, packing means between said shaft and said casing, a control shaft extending outwardly from said valve element and beyond said casing, 50 packing means between said second-named shaft and said casing, means for imparting rocking movement to said drive shaft, and means for rotating said control shaft.

6. In a pump of the character described, a casing, a drive shaft and a control shaft journaled 55 in said casing for rotary movement with respect to each other about the same axis and each extending outwardly beyond said casing, said casing being provided with an abutment disposed therein and concentric about said axis, said drive shaft being provided at its inner end with a pumping element in the form of a segment of a ring complementary to said abutment and concentric about said axis, said pump being provided 60 with an inlet passage for the admission of liquid into said casing between adjacent faces of said abutment and said segment, said pump being provided with an outlet passage for the expulsion of the liquid from between said faces, and means 65

for controlling the volume of liquid expelled through said outlet passage for each stroke of said segment and being in the form of a valve element disposed within said segment and carried by said control shaft for rotation therewith.

7. In a liquid-pressure device of the character described, a casing provided with an annular pressure chamber concentric about its axis, complementary parts disposed in said chamber and each being in the form of a segment of a ring concentric about said axis, one of said parts having a sliding fit in said chamber for rocking movement about said axis relatively with respect to the

other part, said device being provided with an inlet passage for the admission of liquid into said chamber between adjacent ends of said parts, said device being provided with an outlet passage for the expulsion of the liquid from between said ends, and means for controlling the volume of liquid expelled through said outlet passage for each stroke of said rocking part and being in the form of a valve part having a sliding fit with respect to said complementary parts and being rotatable about said axis.

JOHN W. BERHMAN.
